(57) **CLAIM**

The ornamental design for a reversible bib.

DESCRIPTION

FIG. 1 is a front view of a reversible bib, as shown and described;

FIG. 2 is a rear view thereof;

FIG. 3 is a top view thereof;

FIG. 4 is a bottom view thereof; and,

FIG. 5 is a right side view with a left side view being the mirror image thereof.

The broken lines in FIGS. 1 and 2 are for environmental purposes only and form no part of the claimed design.
